SPARK PLUG CRIMPING METHOD AND APPARATUS

Douglas W. Gregory, Trenton, Mich., assignor to
The Firestone Tire & Rubber Company, Akron,
Ohio, a corporation of Ohio

Application May 16, 1941, Serial No. 393,789

2 Claims. (Cl. 219—3)

This invention relates to an improved method and apparatus for use in the manufacture of spark plugs, and more especially to crimping methods and dies used in sealing a spark plug shell around a porcelain of a spark plug.

Heretofore the metal shells of spark plugs have been crimped into engagement with the porcelain in two steps. The first crimping action is effected by a die having a concave or arcuate work engaging face which engages the end of a metal shell and bends it inwardly to cold form a convex peripheral radius on the shell. Next a second die, similarly constructed, is engaged with the metal shell end, the shell being heated to semi-plasticity by electrical current flowing therethrough, and with pressure being applied thereto, said shell collapses to seal upon the gasket and porcelain. In this practice it has been customary to use conforming cold and hot crimp dies. Both dies have to be machined very accurately to insure good contact and prevent arcing and burning at points of poor contact with the shell when sealing a specific size plug. Obviously a large number of dies must be provided to seal the various sizes of spark plugs and the maintenance of the dies is quite costly. The hot crimping operation requires rather high pressures because the conforming hot die provides a rather large contact area for flow of electricity between the die and shell, which of course reduces the current density and tends to keep the section of the shell to be crimped and the gasket contiguous to it cool and rigid. High pressures are very apt to result in cracking of the insulators which in turn makes the plugs defective regardless of the effectiveness of the seal. Furthermore using the old practice it was required to keep the crimp section relatively cold to prevent the annealing of the soft metal having low recalcitrance used in making gaskets. Regardless of this, such gaskets annealed in service under modern high temperature operating conditions.

The general object of this invention is to overcome the foregoing and other objections to previous types of spark plugs shell crimping operations and to provide novel crimping apparatus adapted to make improved seals at the upper ends of spark plugs.

Another object of the invention is to reduce the number of failures in the metal shell occurring during the crimping operation and to reduce the number of dies required in crimping a variety of sizes of spark plugs.

Another object of the invention is to reduce

the crimping pressure required and to provide crimping dies that are easily and inexpensively produced and maintained.

Further objects are to seal spark plugs at higher temperatures than those used heretofore and to use gasket materials which are adapted to withstand high temperatures without annealing. The foregoing and other objects will be manifest as the specification proceeds.

10 In the accompanying drawing:

Figure 1 is a vertical section of a spark plug, shown at the end of the centering operation in the assembly thereof;

15 Figure 2 is a vertical section of the spark plug and crimping apparatus of the invention, the spark plug being shown before and during engagement with the crimping apparatus; and

20 Figures 3 and 4 are detail sections of further crimping apparatus of the invention in its initial and final engagement, with the spark plug of Figure 2 to complete the sealing thereof.

25 Referring in detail to the accompanying drawing, a spark plug 10 is shown therein, which spark plug mainly comprises a metal shell 11 and a porcelain 12. Initially the porcelain, which has an upper shoulder 12^a and a lower shoulder 12^b, is seated on a gasket 13 which is carried on a shoulder 14 formed at the lower portion of the metal shell. An upper gasket 15 is carried on the upper portion of the porcelain 12 and both gaskets 13 and 15 are deformed and the porcelain is centered in the shell by a centering die 16 that is mounted by suitable means (not shown) and moved downwardly thereby to engage with the upper gasket 15 and move it and the porcelain 12 downwardly. This action distorts the gaskets 13 and 15 on the shoulders 12^a and 12^b of the porcelain and centers same in the metal shell. The gaskets are made from a metal such as native lake copper, silver-copper, copper-nickel, or mild steel, all of which have a relatively high recalcitrance or annealing temperature so that they do not anneal readily when in service. Gaskets may be made of relatively hard metals,

45 rather than from soft metals such as copper, since they are hot worked in accordance with the present invention whereas in previous spark plug sealing practice the final working was done at low temperatures. Then too, the gasket materials named hereinabove are relatively soft at high temperatures so that they can be compressed around the porcelain without injuring same.

50 Next a tubular cold crimping die 17, which has a conical face, or work-engaging surface 18, is

brought into engagement with the upper end of the metal shell 11. The face 18 is formed at an angle of about 45° with the horizontal. This shape of the die face is advantageous in that it does not set up excessive compressive strains on the metal shell but gradually folds the upper end of the shell inwardly upon the gasket 15 as the die is moved downwardly upon the upper end of the metal shell. The shell and die are positioned in (and the die moved by) any suitable means (not shown).

Finally a tubular hot crimping die 19, generally similar to the die 17, is brought into engagement with the upper portion of the metal shell 11. The die 19 is mounted on suitable means (not shown), and it and the shell 11 form terminals in an electrical circuit over which current may flow from any convenient source, whereby current flows between the die and the shell when they contact. Such current flow bring the end of the metal shell 11 to a readily workable temperature very rapidly. The die 19 has a conical work engaging face 21 which is shown at an angle of 20° with the horizontal, but which may be at any angle to the horizontal appreciably smaller than that of the face of the die 17. Any angle that is substantially less than 45°, such as from about 5° to about 30°, has been satisfactory for practice of the invention. Then, since the outer surface of the upper end of the shell 11 is at an angle of about 45° with the horizontal, the face 21 first engages with only the upper edge of the shell (Figure 3), rapidly heats it to semiplasticity and folds it inwardly onto and around the gasket 15. Gradually more of the upper surface of the shell comes into engagement with the die 19 as it moves downwardly and the gasket 15 is compressed inwardly and downwardly against the shoulder 12^a of the porcelain 12.

The final position of the component spark plug parts is shown in Figure 4 and it is seen that the inner edge 22 of the crimped section is substantially closer to the porcelain than the inner surface 23 of the shell at the region of maximum distortion. The edge 22 of the crimped shell section entirely covers the gasket 15 and locks it between the porcelain insulator shoulder 12^a and metal shell 11 to form a very effective seal therebetween.

In general, by the gradual engagement of the die 19 with the spark plug shell, higher sealing temperatures, lower compressive forces than those usually used, and the practical employment of gaskets which will not anneal in service result and effect a good seal of the spark plug. Also, a single die can be used with several sizes of spark

plugs and deviation of a spark plug shell from standard form will not prevent the formation of a satisfactorily sealed spark plug therefrom. The working faces of the crimping dies are relatively easily and inexpensively maintained, especially in comparison with concave crimping dies previously used.

The detailed description of the particular embodiment of the invention illustrated and described herein is not to be construed as limiting the invention thereto. The invention includes all features of patentable novelty residing in the foregoing description and the accompanying drawing.

15 What is claimed is:

1. A method of forming spark plugs consisting of the steps of placing a gasket of metal having a high annealing temperature in a metal shell and on an inner shoulder thereof, placing an insulator having an upper and lower shoulder in said shell and seating the lower shoulder of said insulator on said gasket, placing a gasket of material similar to that of the first-mentioned gasket on the upper shoulder of said insulator, centering the insulator and gaskets in the shell by means of a centering die, whereby the shell and insulator is held in spaced relation; next, by a preliminary crimping operation and while the shell is at room temperature, turning the upper edge of said shell inwardly in closer association with the gasket carried on the upper shoulder of the insulator, then softening said shell by means of heat and completing the crimping operation of the upper edge of the shell, thereby anchoring the insulator firmly in said shell and forming an effective seal between the insulator, the gasket and the shell.

2. Apparatus for crimping spark plug shells comprising an apertured die for cold crimping the upper edge of a spark plug shell to approximately the shape desired, said die having a lower corner defining said aperture, and a second apertured die for hot crimping the partially crimped upper edge of a spark plug shell to its ultimate position, means for effecting electrical current flow between said spark plug shell and said second named die upon contact thereof, said last named die being beveled off at an appreciably smaller angle to the horizontal than the said first named die whereby only a small contact area is initially obtained when it is engaged with a spark plug shell initially crimped by said first named die, to produce high density current flow between said second named die and spark plug shell.
